P. TRUSKOWSKI

REIN HOLDER

Filed April 24, 1923

FIG. 4.

Inventor

P. Trushkovski

By

J. R. Bryant.

Attorney,

UNITED STATES PATENT OFFICE.

PAUL TRUSKOWSKI, OF REMSEN, NEW YORK.

REIN HOLDER.

Application filed April 24, 1923. Serial No. 634,267.

To all whom it may concern:

Be it known that I, PAUL TRUSKOWSKI, a citizen of Poland, residing at Remsen, in the county of Oneida and State of New York, have invented certain new and useful Improvements in Rein Holders, of which the following is a specification.

This invention relates to certain new and useful improvements in rein holders and has for its primary object to provide a holding or clamping device for the free ends of reins and which is preferably mounted upon the dash board of a horse drawn vehicle in a manner to prevent accidental disengagement of the reins.

Another object of the invention is to provide a rein holder wherein a sliding wedge member cooperates with the free end of reins and a fixed rein engaging block for effectively retaining the reins within the holder.

With the above general objects in view and others that will become apparent as the nature of the invention is better understood, the same consists of the novel form, combination and arrangement of parts herein-after more fully described, shown in the accompanying drawing and claimed.

In the drawing, wherein like reference characters designate corresponding parts throughout the several views,

Figure 1 is a front elevational view of the rein holder constructed in accordance with the present invention, reins illustrated by dotted lines being operatively positioned therein,

Figure 2 is an end elevational view showing the holder mounted upon the dash board of a vehicle with the ends opening in the holder for receiving the reins,

Figure 3 is a top plan view,

Figure 4 is a horizontal sectional view taken on line IV-IV of Fig. 1 showing the fixed rein gripping block and the sliding wedge member, and

Figure 5 is a vertical cross-sectional view taken on line V-V of Fig. 1 showing the wedging member at its limit of downward movement in the inclined guide slot and the key for moving the wedging member through the slot.

Referring more in detail to the accompanying drawing, there is illustrated a rein holder embodying a base plate 1, preferably rectangular in plan view having a cover casing 2 secured thereto as at 3 and em-

bodying an inclined outer wall as illustrated in Figs. 2 and 5 with the end wall 4 of the cover, and the upper wall 5 thereof together with the bottom wall being cut away at one end as clearly illustrated to provide an end receiving opening for the reins R, shown by dotted lines in Figs. 1 and 2. The edge of the base plate 1 is provided with a plurality of openings 6 to receive fastening devices for securing the rein holder to the inside face of dash board 7.

The rein holding devices are associated with the open end of the cover 2 and include a block 8 carried by the base plate 1 and provided with a roughened or serrated face 9. A partition wall 10 intermediate the ends of the cover 2 cooperate with the end wall 4 of the cover at the open end of the holder to provide bearings for the ends 11 of a wedging cylinder 12 provided with spaced rows of longitudinally extending teeth as clearly illustrated, the ends 11 of the wedging cylinder being slidable in inclined slots 13 formed in the end wall 4 and partition 10 as clearly shown in Figs. 2 and 5, the inclined slots 13 approaching the base plate 1 in directions toward the lower ends thereof to permit the wedging cylinder 12 to be moved into binding engagement with the reins R as illustrated in Fig. 2.

To insure wedging engagement of the cylinder 12 with the reins, the outer wall 2 of the cover adjacent the open end thereof is provided with a slot 14 through which a pin 15 slidably extends, the inner end of the pin carrying a cross head 16 that overlies the wedging cylinder while the outer end of the pin 15 carries an operating button 17.

The reins R are inserted through the end opening in the holder as illustrated in Figs. 1 and 2 and the button 17 is lowered through the slot 14 to cause the cross head 16 to forcibly move the wedging cylinder 12 into engagement with the reins, the latter being wedged between the serrated block 8 and the wedging cylinder 12 and effectively retained or locked therein. To remove the reins from the holder, it is only necessary to impart a slight upward movement thereto and the reins may be easily removed therefrom. It is to be understood that this rein holder does not retain the portions of the reins leading to the horse's head taut, for the device is intended to merely prevent the

loose ends of the reins from falling on to the ground, therefore, the reins leading from the horse's head may be led around either end of the dashboard or over the top of the 5 same laterally of the said rein holder structure.

While there is herein shown and described the preferred embodiment of the present invention, it is nevertheless to be 10 understood that minor changes may be made therein without departing from the spirit and scope of the invention as claimed.

What is claimed as new is:—

1. In a rein holder, a casing having an 15 end opening and an outer wall extending on an incline to the inner wall, a roughened gripping plate therein, and a sliding cylinder wedge cooperating with the gripping plate, there being a slotted opening in the 20 inclined outer wall of the casing and a finger extending through the slot, positioned above the wedging cylinder and operable

exteriorly of the casing for forcing the wedging cylinder into operative engagement with reins.

2. In a rein holder, a casing having an open end, a perpendicular inner wall, a roughened gripping plate formed on said wall, an outer wall extending on an incline to the gripping plate, and a perpendicular 30 slot formed in the outer wall; said casing having inclined slots approaching said plate in directions toward their lower ends, a cylinder wedge slidably mounted in said slot cooperating with said plates, a finger 35 extending through the perpendicular slot positioned above the wedging cylinder and operable exteriorly of the casing for forcing the wedging cylinder into operative engagement with reins.

In testimony whereof I affix my signature.

PAUL TRUSKOWSKI.
